UNITED STATES PATENT OFFICE.

FREDERIC P. GATES, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,337,011.

Specification of Letters Patent. Patented Apr. 13, 1920.

Application filed May 8, 1919. Serial No. 295,658.

To all whom it may concern:

Be it known that I, FREDERIC P. GATES, a citizen of the United States of America, residing in the city of Hartford, county of 5 Hartford, and State of Connecticut, have invented a certain new and useful Improvement in Electric Switches, of which the following is a specification.

My invention relates to electric switches, 10 and particularly to flush switches, the object of my invention being to provide an improved operating mechanism for the switch, and an improved fastening device for holding the cover plate in position on 15 the switch body.

In the accompanying drawings—

Figure 1 is a broken plan of a switch in which my invention is embodied in one form;

20 Fig. 2 is a broken side elevation thereof; Fig. 3 is a longitudinal section through the switch;

Fig. 4 is a section on the line 4—4 of Fig. 3; and

25 Fig. 5 is an exploded view of certain associated elements of the switch mechanism.

While certain features of the present mechanism may be embodied in switches of 30 various types, I have here shown the invention applied to a flush switch adapted to be mounted in the usual fashion in a concealed outlet box, the installation being finished by a cover plate secured to the switch. As here shown the switch com-

35 prises an insulating body formed from two blocks of insulating material 10 and 11, recessed on their meeting faces to form a switch chamber 12 within which the switch terminals and switch bar are confined. The

40 blocks 10 and 11 are held in assembled position by a pair of bolts 13 and 14 piercing the end portions of the blocks and taking into straps 15 and 16 by means of which the switch is mounted in an outlet box in a well

45 known manner. The switch illustrated is of a double pole type, having four wire terminals 17, 18, 19 and 20 by which the current is led to the co-operating pairs of terminals 21 and 22, 23 and 24, all of well

50 known type. The switch bars 25 and 26 make and break the circuit between these terminals with a snap action under the influence of a switch spring 27. This spring is coiled upon the axis 28, and its legs 29

55 and 30 straddle the two bridge pieces 31

and 32, the former extending between the opposite sides of the rocker 33 and the other extending between opposite sides of the switch bar carrier 34 to which the switch bars are secured, but insulated therefrom by 60 insulating washers 35. The rocker is journaled upon the axis 28, and its opposite side pieces are provided with inclined bearing surfaces 36 against which work the shoulders 37 of the push plates 38 and 39, which are rectilinearly guided in the slots 40 and 41 formed in the opposite sides of the frame member 42. The latter is secured in position by screw bolts 43 and 44, which pierce the block 10 and take into tapped holes 45 70 and 46 in the base of the frame.

To actuate the push plates 38 and 39 I have provided a lever 47 oscillating on the axis 48 and provided at its inner end with a pair of cam arms 49 and 50, the lower 75 cam faces of which bear against the push plates and are guided in slots 51 and 52 therein. At its outer end the lever 47 has secured thereto a thumb piece 53 projecting beyond the face plate 54 into position to be 80 actuated by the operator, and by which the lever may be swung on its axis 48. As here shown, the thumb piece 53 is separate from the lever 47 and comprises a pair of legs 55 which straddle the stem of the lever 47, 85 which is preferably struck from sheet metal, and to which they are secured by a rivet 56, and by the pivot pin 48 which forms the axis of oscillation.

Obviously, when the thumb piece 53 is 90 swung on its axis its motion is communicated to the lever 47, and its cam arms 49 and 50 are shifted. In Fig. 3 the switch is shown in "on" position. When the thumb piece 53 is swung to the right the 95 arm 50 is depressed, and the arm 49 elevated. During the downward swing of the arm 50 its cam surface slides across the push plate 39 and depresses the latter. As the push plate moves downward its shoulders 37 bear upon the cam faces 36 of the rocker 33 and cause the latter to oscillate on the axis 28. The bridge piece 31 of the rocker moves to the left, carrying with it one of the ends of the switch spring 27, 100 thus placing the latter under tension inasmuch as the switch bar carrier 34 is temporarily detained against oscillation by its lugs 57, which temporarily bear against the detaining margins 58 of the push plates 38 110

and 39. When the push plate 39 has moved a predetermined distance downward and the push plate 38 a corresponding distance upward under the action of the rocker, the 5 lugs 57 escape the margins 58 of the push plates, and the switch bar carrier 32 is then swung with a snap action into the "off" position of the switch under the influence of the switch spring 27 in a well understood 10 manner.

The support for the lever 47 is afforded by a pair of standards 59 and 60 rising above the base of the frame 42 and terminating in arcuate segments 61 and 62 pierced in 15 register at 63 to accommodate the pivot pin 48. While these standards 59 and 60 might be formed integral with the frame 42, or be riveted thereto, I have here shown them carried by a complementary frame member 20 having a base 64 overlying the base of the switch frame 42 and perforated at 65 to permit the passage of the bolts 43 and 44 therethrough so that this complementary frame member is clamped in position by the same 25 bolts which hold the main frame 42 in position. Both frames 42 and 64 are apertured at 66 and 67 to permit the actuating lever 47 to pass downward therethrough into operating position.

30 The face plate 54 overlies the body of the switch and is apertured to permit the standards 59 and 60 to pass therethrough, the shape of the aperture being generally circular to conform to the shape of the arcuate 35 segments 61 and 62, but being interrupted by lugs 68 which project into the space between the segments and thus serve to position the face plate accurately with relation to the switch body. The face plate is held 40 in position by a ferrule 69 screwing upon the arcuate segments 61 and 62 and bearing against the outer face of the face plate. The central aperture 70 in the ferrule permits the thumb piece 53 to pass therethrough, and in order to close this aperture 45 against the admission of dirt and moisture to the interior of the switch the thumb piece is provided with a hub 71 which completely closes the aperture in all positions 50 of the switch.

The precise details of the structure indicated may be variously modified by those skilled in the art without departing from what I claim as my invention.

55 I claim—

1. An electric switch comprising an oscillating rocker, a pair of rectilinearly guided push plates, an oscillating lever bearing upon said push plates and having a sliding 60 engagement therewith, together with an

oscillating thumb piece associated with said lever for swinging the latter on its axis.

2. An electric switch comprising an oscillating rocker, a pair of rectilinearly guided push plates, an oscillating lever bearing 65 upon said push plates and having a sliding engagement therewith together with an oscillating thumb piece associated with said lever for swinging the latter on its axis, said thumb piece and lever being rigid with relation to each other and oscillating on the 70 same axis.

3. In an electric switch, an oscillating rocker, a pair of rectilinearly guided push plates for operating the same, a frame hav- 75 ing a base with guide wings for the push plates projecting from one side of said base, a pair of standards projecting from the opposite side of said base, an oscillating lever pivoted in said standards, and arms on said 80 lever in sliding engagement with the push plates to shift the latter in opposite directions simultaneously in their guideways.

4. In an electric switch, a switch frame, comprising a base, members projecting in 85 one direction from said base, a switch bar pivoted in said members, standards rigid with said base in the assembled switch and projecting in the opposite direction from said base, a rocking lever pivoted in said 90 standards, and mechanism operatively interposed between said rocking lever and switch bar and actuated by said lever for actuating the switch.

5. In an electric switch, a frame member 95 comprising a pair of standards having arcuate flanges, a cover plate apertured to permit said flanges to project therethrough, and a ferrule screwing on said flanges and bearing against said cover plate to hold the 100 latter in position, together with lugs on said face plate engaging between said arcuate flanges of the standards and serving to position the face plate with relation to said frame element. 105

6. In an electric switch, a frame comprising a base having guide members projecting from one face thereof, and standards rigid with said base in the assembled switch and projecting from the opposite face thereof, switch mechanism carried by one of said members, and an operating lever carried by the standards and coöperating with said switch mechanism to operate the latter, a face plate overlying the switch, and means 110 engaging the standards to hold said face plate in position.

In testimony whereof I have signed my name to this specification.

FREDERIC P. GATES.
